[57] ABSTRACT

A cover with depending nesting sides, the upper parts

of which telescope into a lower part. The cover and sides adjoining are lined with refractory material. Intermediate the lining and the cover a sprinkler system is mounted to provide a descending spray of cooling and fire extinguishing material. The apparatus is adapted to be lifted by its lower part with upper parts telescoped therein by a floating crane and lowered by cables over a burning off-shore oil rig and such like to enclose it from top to below sea level. Vertical adjustable jacks are mounted to depend from said cover and engage the top of the working platform of an oil rig to space it from said platform and support the apparatus when it is fully extended downward. The sides, extending below sea level, define an enclosed reservoir area for catching liquid pollutants. A conduit is mounted in the lower part of said sides, an end of which is supported at sea level in the reservoir area, and another end of which extends outwardly of the sides for discharging liquid pollutants in said reservoir area to salvage barges brought alongside. The telescoping sides are roller bearinged between sides and at corners to provide non-frictional and non-jamming operation. A hatch and depending ladder are mounted in the cover to provide access to work platform after fire is smothered for repairing the rig and stopping the flow of oil to the reservoir area.

FIG. 3

FIRE SMOOTHERING AND OIL CATCHING
APPARATUS FOR USE WITH OFFSHORE OIL
RIGS

The invention relates generally to fire smothering apparatus and more particularly to a fire smothering and oil catching apparatus for putting out off-shore oil rig fires.

It is old in the art to blow out oil rig fires with explosives with probable attendant damage to the rig and to extinguish fires with extinguishing materials. Often fires have to be restarted after they have been put out in order to burn the escaping oil to prevent pollution of the sea and adjacent shores.

It is an object of the invention to provide dual means for smothering fires on off-shore oil rigs without adding to the damage inflicted by the fire, and for catching escaping oil for removal in salvage barges.

Other objects and a more complete understanding of the invention may be had by referring to the following specification, claims and drawings, in which:

FIG. 1 is a side elevation of the invention being lowered over an off-shore oil rig,

FIG. 2 is a plan view of the invention in place an enclosing said oil rig, and

FIG. 3 is an enlarged partial cross-section taken along section lines 3—3 of FIG. 2.

Referring to FIG. 1, a crane barge 10 mounts a crane 12 which suspends the invention of telescoping parts 14 by a cable 15, attached to the lowest of said parts, over a burning off-shore oil rig 16.

Referring to FIGS. 2 and 3, the invention comprises three rectangular sections 18, 20 and 22, respectively, that are vertically arranged to successively telescope downward from the section next above. Smallest section 18 comprises a top cover 24 and depending sides 26 that are adapted to enclose the top of oil rig 16. Intermediate rectangular section 20 comprises depending sides 28 that are spaced apart sufficiently for section 18 to telescope therein. Similarly the lowest section 22 comprises depending sides 30 that are spaced apart sufficiently for section 20 to telescope therein. The telescoping sections are guided in their vertical movement by corner roller bearings 32 and facilitated in their movement by side roller bearings 34, said bearings being mounted between relatively telescoping sections.

Referring specifically to FIG. 3, a heat resistant liner 36 is mounted in section 18. The liner can be made of any of a number of well known refractory materials. A sprinkler system 38 is mounted between the liner 36 and the top cover 24 of section 18 for the dual purpose of helping extinguish a fire and to cool both the cover and the burning rig. Vertically adjustable jacks 42 are mounted in the cover 24 and depend to engage working platform 44 of rig 16. The jacks 42 support the invention 14 over and around rig 16 and space the cover 24 thereabove. A hatch 46 is provided in the top cover 24, and a ladder 48 pivotally mounted thereunder provides access to the rig when the fire is put out.

Intermediate section 20 has an inwardly extending upper flange 50, and an outwardly extending lower flange 52 with an oppositely disposed stop 54. An outwardly extending flange 56 fixed to the lower end of sides 26 engage flange 50 and stop 54 of sides 28 to prevent the disengagement of sections 18 and 20 at the respective opposite ends of their relative telescoping movement.

Lower section 22 has an inwardly projecting flange 58 fixed to its upper end a similarly projecting stop 60 fixed to its lower end. They cooperate with flange 52 of section 20 to prevent disengagement of sections 20 and 22 at the respective opposite ends of their relative telescopic movement. Padeyes 62 are defined in flange 58 in which cables 15 engage to hold the invention in descending suspension. When the invention is fully extended, it is held in suspension by jacks 42. A conduit 64 is mounted on side 30 and has an end 66 that passes under stop 60 and rises to sea level within sides 30. Another end 68 is threaded to engage a hose (not shown) from a salvage barge (not shown) into which oil is pumped outwardly from within sides 30.

The combined lengths of sides 26, 28 and 30 are determined to extend below sea level at least but above the bottom of the sea. This enclosed below sea level area 70 acts as a catch basin for escaping oil.

In operation the sprinkler system 38 is connected to an outside source of cooling and fire extinguishing liquid (not shown) and turned on. The invention 14, protected by the liner and cool spray from melting is hoisted over the burning oil rig 16. Since the hoisting cables 15 engage the lower section 22 with sections 18 and 20 telescoping downward by gravity to stops 54 and 60 respectively, the height of the lift is reduced by the combined heights of those sections. With the vertically adjustable jacks 42 set for top cover 24 and liner 36 to clear any upwardly extending gear on work platform 44, the invention is lowered over the top of the oil rig. When jacks 42 engage platform 44, section 20 telescopes downward along sides 26 of section 18 until flange 50 of section 20 engages flange 56 of section 18. As the lowering continues, section 22 telescopes downward along side 28 of section 20 until flange 58 of section 22 engages flange 52 of section 20.

The burning rig is now completely enclosed from top to below sea level. The smothering action of the enclosure plus the extinguishing action of the sprinkler system puts out the fire by denying it supporting oxygen. Oil escaping from damaged well strings falls into the enclosed area 70 and floats therein to force water downwardly out to the depth side 30 extends below sea level. This oil can be evacuated to salvage barges before it forces all water from area 70 to escape and pollute surroundings.

The sprinkler system is turned off when the rig is cooled enough for men to open the hatch 46 and purge the enclosure of products of combustion and to ventilate by means not shown but well known.

Referring to FIGS. 2 and 3, the apparatus is suspended over a burning oil rig by a bridle 72 comprising a center frame work 74 which is attached by its center 76 to the crane. Cables 15 extending from the ends of the frame work pass around sheaves 78 mounted in the corners 80 on projections 82 (only one indicated on FIG. 2) that center the respective sheaves over respective padeyes 62.

A first hatch 46 is used for introducing equipment into the burning oil rig, and a second corner hatch is provided for the entrance of workmen. Both hatches are used for ventilation after the fire is extinguished on the rig.

Seals can be installed between telescoping parts and a side hatch provided in intermediate section 20 for opening after a fire is out. The seals are to prevent leakage of fire supporting air and oxygen into the enclosure

before the fire is out, and the hatch is to provide air to scavenge the products of combustion and heat from the enclosure after the fire is out.

What is claimed is:

1. Fire smothering and reservoir forming apparatus for use in combination with a floating crane in fighting off-shore oil rig fires, and comprising covering means having upper and intermediate parts telescopically connected for enclosing in extension said oil rig above sea level; refractory lining means mounted in said upper part of the covering means for heat shielding said upper part; reservoir means axially and telescopically joined to said intermediate part to extend below seal level for defining a storage space under said oil rig for the capture and retention of escaping pollutants; stop means mounted on said upper and intermediate parts and on said reservoir means for respectively retaining them in telescopic connection; and suspension means fastened to said floating crane and to said reservoir means for suspending said fire smothering and reservoir forming apparatus in nesting condition over said oil rig and lowering it into engagement therewith to enclose said rig from below sea level to its full extent above sea level.

2. Fire smothering and reservoir forming apparatus as described in claim 1 wherein said covering means upper part comprises: a closed cover with depending sides; hatch means defined in said closed cover for providing entrance and ventilation to enclosed oil rig after a fire is extinguished.

3. Covering means upper part as described in claim 2 wherein said closed cover includes a cooling means mounted therein for cooling said covering means upper part.

4. Closed cover as described in claim 3 wherein said

cooling means comprises: a sprinkler means having an external input conduit passing through said closed part and a plurality of output nozzles vertically directed downward in said upper part; and a fire extinguishing liquid coolant means adapted for external delivery to and internal delivery from said sprinkler means for cooling said upper and said oil rig and for helping to extinguish a fire thereon.

5. Covering means upper part as described in claim 10 2 wherein said closed cover includes depending vertically adjustable jacks mounted therein and adapted to engage said oil rig and vertically support and space said closed cover thereabove with depending sides therearound.

15 6. Fire smothering and reservoir forming apparatus as described in claim 1 wherein said telescoping upper and intermediate parts, and said reservoir means are respectively spaced apart by roller bearings mounted therebetween for reducing telescoping friction.

20 7. Telescoping parts and reservoir means as described in claim 6 wherein said parts and reservoir means are rectangularly shaped and roller bearings mounted between corners thereof define right angles for guidance thereof and the prevention of jamming therebetween.

25 8. Fire smothering and reservoir forming apparatus as described in claim 1 wherein said suspension comprises: a flexible bridal fixed to said crane and detachably connected to said reservoir means for suspending said telescoping parts and means in collapsed condition over a burning oil rig, and lowering it progressively to full extension to enclose said rig to below sea level.
